DESIGN FOR A DISPLAY CARTON

Edward Funke, Pelham Manor, N. Y.

Application December 4, 1937, Serial No. 73,373

Term of patent 3½ years

To all whom it may concern:

Be it known that I, Edward Funke, a citizen of the United States, residing at Pelham Manor, county of Westchester, and State of New York, have invented a new, original, and ornamental Design for a Display Carton, of which the following is a specification, reference being had to the accompanying drawing, forming a part thereof.

I claim:

The ornamental design for a display carton as shown.

EDWARD FUNKE.
